UNITED STATES PATENT OFFICE.

CARL ALBERT EISSNER, OF LUGAN, SAXONY, GERMANY.

TILE-CUTTING MACHINE.

SPECIFICATION forming part of Letters Patent No. 398,885, dated March 5, 1889.

Application filed February 20, 1888. Serial No. 264,610. (No model.) Patented in Germany September 28, 1887, No. 44,518; in Belgium January 31, 1888. No. 80,241, and in France March 26, 1888, No. 188,107.

To all whom it may concern:

Be it known that I, CARL ALBERT EISSNER, a subject of the Emperor of Germany, and a resident of Lugan, in Saxony, Germany, have 5 invented an Improvement in Machines for Cutting Clay in the Manufacture of Bricks and Tiles and for Like Purposes, (for which I have obtained Letters Patent in the following countries, namely: Germany, No. 44,518, dated 10 September 28, 1887; France, No. 188,107, dated March 26, 1888, and in Belgium, No. 80,241, dated January 31, 1888,) of which the following is a specification.

This invention relates to the cutting into 15 equal or predetermined lengths such material as clay fed from a brick-press, and other material fed continuously with equal or varying velocity.

The improvement consists, first, in the manner of and direct means for actuating the cutters, and, secondly, in the mechanism or gear by which the movement of the material sets the actuating mechanism in motion, so that the cutting of the material is rendered dependent on the feed movement thereof.

Referring to the accompanying drawings illustrating the invention as applied to the cutting of oblong and circular sections, Figure 1 shows the material, *a*, issuing from the tube *c* of the brick-press. Fig. 2 shows in side elevation the cutters and mechanism for operating them. Fig. 3 is a plan view of said cutters and mechanism. Figs. 4, 5, and 6 show different contrivances to be operated by friction of surface of the clay for the setting in action at certain intervals of the mechanism controlling the cutters. Fig. 7 is an enlarged elevational view of one of the piston-valves.

40 The cutters consist of wires or double-edged knives, and there may be one or more cutters. The said cutters are fixed between the arms of a bow-frame, *k*, having a downward extension pivoted on a rocking shaft or pin, the depth of said bow-frame being sufficient to permit of free passage of the material (hereinafter called "the blank") through the bow. The bow is connected directly or indirectly to the piston-rod *q u*, the piston 45 being movable by steam-pressure back and forth in the cylinder *l*. The stroke of the piston is sufficient to move the cutters through the blank alternately back and forth.

A drum, *b*, (*g*, *h*, or *i*) or pair of drums,

having a shape of periphery as Figs. 3, 4, 5, 55 or 6, according to the shape of section of the blank to be cut, are carried upon shafts journaled so that the superficial friction of the drum or drums on the advancing blank causes the rotation of the drums. On the 60 shaft of one of the drums is a miter-wheel, *m*, gearing into a similar miter-wheel, *m'*, on the shaft *m*. On the shaft *m* are fixed two tumblers, *o o'*, adapted as the shaft rotates to rise under and lift levers or arms *e*, connected 65 with the steam inlet and outlet ports *p* and *f*, respectively, in connection with one end of the cylinder *l* aforesaid. The shaft *m* is geared with the shaft *m*, and carries likewise similar tumblers, *o² o³*, adapted to raise 70 levers connected with the inlet and outlet valves *p' f'* of the other ends of the cylinder. The tumblers *o o' o² o³* are so arranged that when the inlet-valve is open at one end the outlet-valve is open at the other end. It will 75 be seen, therefore, that since the feeding motion of the blank controls the operation of the cutters, the blank is cut into equal or predetermined lengths without necessitating steady feed of the blank. It is therefore of great 80 advantage with hand-presses.

The diameter of the friction-drums *b* determine the length of the blank cut at each passage; or, if more than one cutter, being fixed in the bow *k*, the aggregate length of the sections cut off at each passage of the cutter. The blank is supported by rollers so arranged as to permit of the passage of the cutters between them. The cutter-operating machinery may likewise be set in action by mechanism controlled by a block or other object carried forward with or by the advancing blank.

I claim—

The combination, with a bow, *k*, carrying 95 cutters, of a cylinder, *l*, having inlet-valves *p p'* and outlet-valves *f f'*, a piston in said cylinder having rod *q u*, adapted to move said bow *k* back and forth, friction-drum *b*, and tumblers *o o' o² o³*, revolved by gear from 100 said drum, for the purpose set forth.

In testimony whereof I have signed my name to this specification in the presence of two subscribing witnesses.

CARL ALBERT EISSNER.
